TELEMEETER

Jacob L. Zar, Orange, N. J., assignor to Thomas A. Edison, Incorporated, West Orange, N. J., a corporation of New Jersey

Application April 19, 1944, Serial No. 532,024

13 Claims. (Cl. 177—351)

1

This invention relates to telemetric systems and more particularly to a novel and improved telemetric system of the three-phase type which employs a transmitter of the single brush or single contact form and a receiver utilizing a permanent magnet rotor.

It is an object of my invention to provide novel telemetric systems of the character mentioned which have a greater accuracy in adhering to a linear response characteristic than has been heretofore obtained.

It is another object to provide novel telemetric systems of the character mentioned which have substantially linear response characteristics throughout a 360° scale range.

Another object is to provide novel and improved receiving instruments for telemetric systems of the character mentioned.

Other objects are to provide telemetric systems of the character mentioned which are efficient and reliable, and which are adapted to permit wide manufacturing tolerances in their several components.

In my invention, the rotor of the receiver is controlled wholly by the field coils without the use of any intervening magnetic materials between the rotor and the surrounding magnetic shield, it being of course understood that the field coils are mounted on suitable non-magnetic cores or supports. According to my invention I may provide innumerable designs of such receivers to meet different conditions, each of which will reproduce accurately and linearly the settings of the transmitter. By my invention, I am able to prescribe the physical parameters of these different designs. For instance I find that the desired torque characteristic of the receiver can be prescribed in terms of the electrical circuit parameters of the telemetric system and that the dimensions and locations of the field coils can be prescribed in terms of the magnetic characteristics of the rotor receiver.

These and other objects and features of my invention will more fully appear from the following description and the appended claims.

In the description of my invention reference is had to the accompanying drawings, of which:

Figure 1 is a circuit diagram of the type of telemetric system to which my invention relates;

Figure 2 is a graph showing one prescribed torque characteristic for the receiver of the telemetric system;

Figure 3 is a graph showing the percentage third harmonic in the torque characteristic rela-

tive to the electrical parameters of the circuit of the telemeter;

Figure 4 is a view illustrating one form of receiving instrument according to my invention;

5 Figure 5 is a plan view of a preferred shape of magnet for use with the receiving instrument of Figure 4;

Figure 6 is an elevational view of the magnet of Figure 5;

10 Figure 7 is a graph showing the approximate flux distribution for the magnet-shield arrangement of Figures 5 and 6;

Figure 8 is a diagrammatic view showing a second embodiment of receiver according to my invention;

15 Figure 9 is an elevational view showing a preferred shape of magnet for the receiver of Figure 8;

Figure 10 is a graph showing the approximate flux distribution for the magnet-shield arrangement of Figure 9;

20 Figure 11 is a view showing a third embodiment of receiver according to my invention wherein two coils are used per phase;

25 Figure 12 is a plan view of a preferred shape of magnet for use with the receiver of Figure 11;

Figure 13 is an elevational view of the magnet of Figure 12;

30 Figure 14 is a graph showing the approximate flux distribution for the magnet-shield arrangement of Figures 12 and 13; and

Figure 15 is a view of a receiver having the operating characteristics of the receiver of Figure 11 but with a different coil arrangement.

35 In Figure 1 there is shown a circuit diagram of the type of telemetric system above-mentioned. This telemetric system includes a transmitter T and a receiver R. The transmitter comprises a closed circular resistor which may be a wire helix

40 11. This helix has uniformly distributed resistance and is provided with three taps 2 equidistantly spaced at 120° intervals. At the center 3 of the helix 11 there is provided a single brush or contact arm 4 which slidably engages the

45 helix. The receiver R comprises a rotor magnet 5 pivoted at 6, and three similar field coils 7—or sets of coils as will hereinafter appear—which are spaced equidistantly about the magnet at 120° intervals. The coils are star connected

50 (specifically, in the form of an electrical Y) to the respective taps 2 by lead wires 8 and the common junction 9 of the coils is connected by a lead wire 10 and through a battery B to the contact arm

55 4. The field coils are to have substantially equal resistances, the degree of variation which may

be tolerated between coils depending upon the accuracy desired; and to compensate for variations between coils in manufacturing there may be inserted a small resistance $1a$ in series with any one of the field coils of lower resistance.

It will be understood, as is well known in electric circuit theory, that for each position of the contact 4 the magnetic fields of the three field coils combine to produce a resultant magnetic field, and that the direction of this resultant field will vary with the positioning of the contact arm. The rotor magnet, which is magnetized on an axis at right angles to its pivot axis, will assume the position wherein its magnetic axis is aligned with the direction of that resultant field. Accordingly, as the contact arm 4 is turned the rotor will turn likewise, and the corresponding positions of the rotor will be indicated by a pointer 12 relative to a scale 13 on a dial 14 . Since in this telemetric system the currents in the field coils represent three phases, in respect of their spatial relationship about the pivot axis of the receiver as a center, the system is commonly referred to as being of the three-phase type. For reasons which are apparent from the foregoing description, the transmitter is known as of a single-contact type and the receiver as of the permanent-magnet-rotor type.

In telemetric systems it is desired that the receiver pointer shall indicate accurately the positioning of the transmitter arm or contact throughout the range of travel of the latter. When the pointer of the receiver assumes positions corresponding substantially exactly with those of the transmitter arm throughout the whole scale range, then the scale divisions of the receiver may be evenly or linearly spaced, and the system will have a so-called linear response characteristic. It will of course be understood that a linear response is highly desirable, particularly in that the general positioning of the pointer can then be relied upon for an approximate reading without reference to any scale or dial; also, a linear characteristic facilitates manufacturing and calibration of the telemeter in production.

The different designs of my invention are arrived at by varying the ratio of the resistances of the field coils to the resistance of the transmitter, by varying the shape of the rotor magnet and by varying the shape and location of the field coils. These parameters cannot however be varied independently of one another as they must all be held to a predetermined relation in order to obtain a linear response. Basically, the significance of the ratio between the resistances of the field coils and the transmitter is that it establishes the torque deflection characteristic of the receiver which is required for obtaining a linear response. As will be apparent from the following description, each such chosen or established torque deflection characteristic may be realized by innumerable combinations of rotor magnets and field coils.

The term "torque deflection characteristics" is used herein to mean the variation in restoring torque exerted by the field coils on the rotor magnet as the magnet is forcibly deflected from an equilibrium position. It will for example be understood that for each position of the transmitter arm 4 there is such position of equilibrium for the rotor magnet, this position being one wherein the magnetic axis of the magnet is aligned with the direction of the resultant magnetic field of the field coils. As the rotor magnet

is forcibly deflected from such equilibrium position, a restoring torque is exerted by the interaction of the field coils on the magnet, to return it to that equilibrium position, which increases to a maximum and then falls off to zero as the rotor magnet is deflected to 180° from equilibrium position; at this point, the rotor magnet is in a condition of unstable equilibrium. With further deflection of the rotor magnet, the restoring torque increases to a maximum in the opposite direction and then again falls back to zero as the magnet is returned to its initial equilibrium position. This variation in restoring torque with deflection is thus of a sinusoidal character which may be represented by a Fourier series. When the field coils, or sets of coils, are identical and the magnet is symmetrical to its pivot axis—which are the conditions herein considered—the shape of the torque deflection characteristic, or torque curve as it may be termed, through the first 180° deflection from equilibrium position is the same, except for direction, as through the second 180° deflection, and the Fourier series thus comprises only a fundamental and odd-numbered harmonics. This Fourier series may be written as follows:

$$\text{Torque} = \sin \theta + b \sin 3\theta \quad (1)$$

where b is the fraction or percentage of third harmonic and θ is the angle of deflection of the rotor magnet from equilibrium position. While this torque curve may include higher odd-numbered harmonics than the third, these higher harmonics have a lesser order of importance and need not be considered for purposes of my invention.

It is found that the shape of the torque curve determines the accuracy with which the receiver shall linearly follow the movement of the transmitter contact arm. This shape of the torque curve can be expressed in terms of the percentage of its third harmonic component. By my invention, I find that a substantially negligible error in linearity is obtained when

$$b = -\frac{13/r}{3+r/l} \quad (2)$$

where r is the resistance of each section of the helix 11 between the taps 2 ($3r$ being the resistance of the whole helix) and l is the resistance of each field coil 1 . A graphical representation of this equation appears in Figure 3, where the ordinates represent the fraction of third harmonic b and the abscissas represent the ratio of r/l . As a typical case each transmitter section may have a resistance equal to twice that of each field coil giving the ratio of r/l a value of 2. For this value of r/l there is required a coefficient of third harmonic b of approximately -5.2% of the fundamental—as may be determined by reference to Equation 2 or the graph of Figure 3—in order to obtain a substantially linear response. In Figure 2, there is shown a torque curve having approximately this percentage of third harmonic. This torque curve is to be obtained irrespective of the specific design of the receiver so long as the resistances of the transmitter sections are twice the resistances of the respective field coils. For other resistance ratios, different percentages of third harmonic are required according to the above Equation 2. I now show how the required torque curve is obtained by different specific designs of the receiver.

It will be realized that the only intrinsic difference between rotor magnets of different shapes

lies in the differences in their magnetic fields, or what may be termed their "flux field distribution." By the term "flux field distribution" is meant the effective field strength of the rotor magnet at various angles from the magnetic axis of the magnet about the pivot axis as a center, it being understood that the field strength is to be considered under actual operating conditions—that is, with a surrounding magnetic shield as is shown in the following specific embodiments. For any given rotor magnet and surrounding field, the flux field distribution may be measured by interposing a conductor between the magnet and shield, rotating the magnet at uniform rate, and measuring the induced voltage in the conductor. A graph of the induced voltage will have the same shape as that of the flux field. For symmetrical magnets, as are here considered, the magnetic field strength H may be represented by a Fourier series comprising a fundamental and odd-numbered harmonics. Again, only the third harmonic need be considered, wherefore the magnetic field may be written as:

$$H = \sin \phi + d \sin 3\phi \quad (3)$$

where d is the fraction of third harmonic and ϕ is the angle between the magnet and the conductor abovementioned. This equation is wholly analogous to the torque curve of Equation 1.

Preferably, I use rotor magnets which are relatively long compared to the internal diameter of the surrounding shield—that is, of the order of at least half the length of the shield diameter—as then the tolerances on the magnet are less critical and a greater accuracy in response is obtained. The use of such "long" magnets greatly facilitates the design of the receiver because with such magnets the flux in the air gap between the magnet and the surrounding shield is confined closely to the plane of the magnet and the only part of the field coils which are instrumental in determining the response characteristic of the receiver are the longitudinal legs thereof which are intersected by the magnet flux. Thus the only significant dimensions of the coils are those of their longitudinal legs; the transverse or crossover legs, being outside the magnetic field, may have any convenient shape without affecting the response of the receiver.

By my invention I am able to specify the positions and dimensions of the longitudinal legs of the field coils in terms of the fraction d of third harmonic in the flux field distribution and the fraction b of third harmonic in the torque curve. This relationship is now illustrated in terms of a specific embodiment of receiver according to my invention.

In Figures 4, 5 and 6 there is shown a receiver comprising a rotor magnet 15 which is preferably made of a highly efficient permanent magnetic material such as one of the "Alnicos." The magnet is pivoted for rotation about an axis 16. Surrounding the magnet 4 is a shield or sleeve 17 which is preferably made of a non-permanent and highly permeable magnetic material such as "Mumetal." This is a cylindrical shield positioned concentrically to the pivot axis 16 so that the magnetic field of the rotor is the same for all positions thereof, and the rotor is without any magnetic bias. This insures that the same value of d (of Equation 3) holds for all positions of the rotor magnet. Within the shield 17 there are three identical field coils 18. These coils are so positioned that the opposite legs 18a, hereinbefore referred to as the longitudinal legs, will lie par-

allel to the pivot axis of the meter, between the magnet and shield, with the axes of the coils intersecting the pivot axis and spaced at 120° intervals thereabout. The significant dimensions of the longitudinal legs 18a of each coil are their angular span and their angular widths. By "angular span" is meant the angle subtended by radial lines running from the pivot axis 16 to the centers of the legs 18a, and by the "angular width" is meant the angle which the legs subtend about the pivot axis as a center. These significant dimensions of each field coil are given in my invention by the equation:

$$(3 - 4 \sin^2 x)(3 - 4 \sin^2 g) = -\frac{3b}{d} \quad (4)$$

where b and d are the fractions of third harmonic in the torque and flux curves as aforementioned, g is one-half the angular width in degrees of the legs 18a of each coil and x is one-half the angular span in degrees of each coil as above defined. Or alternatively, by expressing b in terms of the ratio r/l , and transferring terms, this equation may be expressed as:

$$d = \frac{.39r/l}{(3 + r/l)(3 - 4 \sin^2 x)(3 - 4 \sin^2 g)} \quad (4a)$$

These formulae give the relation between all the significant parameters of the telemeter system for obtaining a linear response.

It may be pointed out by way of example that Equation 4 may be used as follows: An approximate ratio of r/l is first chosen—which ratio is not critical. This value is substituted in Equation 2 to find the value of third harmonic in the torque curve, which is the quantity b . An appropriate magnet is then chosen, and its flux field distribution is measured as for example by the method aforescribed. The flux curve is then analyzed, by standard Fourier analysis, to determine the fraction of third harmonic d . A value for the span of the field coils is then selected and, with these values, Equation 4 gives the angular width of the legs 18a which is required to obtain a linear response.

A preferred span for the field coils is 180° for with such coils the tolerances are less rigid and a maximum coupling coefficient is obtained to give a maximum torque efficiency. For this span of field coil there may be suitably used a magnet having an approximately ellipsoidal shape as shown in Figures 5 and 6. As a typical case, for a shield 17 having a 1" inside diameter, the magnet may have a length along its major axis of $5\frac{1}{8}$ ", a length along its minor axis of $1\frac{1}{2}$ "; the ends of the magnet may terminate in arcs of $1\frac{1}{8}$ " radii about the pivot axis as a center, and the sides may terminate on arcs of $1\frac{1}{2}$ " radii about the ends of the minor axis as centers; and the thickness of the magnet may be $1\frac{1}{16}$ " at the center and may terminate to $\frac{1}{16}$ " at the ends. The magnet is charged along its major axis between two flat poles with air gaps, and the major axis is then also the magnetic axis hereinbefore referred to.

The magnet above described has a flux distribution characteristic approximately as represented by the graph of Figure 7, which curve has a fraction of third harmonic d of the order of approximately $-.053$. On the basis that the torque curve of Figure 2 is to be obtained, the coefficient of third harmonic b is $-.052$ as aforementioned and for 180° coils the value of x is 90° . Using these values in Equation 4 it is found that g shall be 7° , which means that each coil leg 18a shall

be 14° wide. When the coil legs have this width, for the values above considered, there will be obtained a linear response.

It will of course be understood that as an alternative procedure the dimensions of the coils may be first assigned, in terms of their span and the width of their longitudinal legs, as also may be the value of r/l , and that then the value of d may be computed by the Equation 4a. Having determined d , I then find the shape of magnet—
which may be done by trial—that will have a flux curve with this fraction d of third harmonic.

Since the field coils have 180° span and are spaced 120° apart, their cross-over legs 18b must necessarily overlap. Preferably, I make the three field coils identical but with one of the longitudinal legs 18a, of each coil longer than the other leg of the same coil so that, in the assembled meter, each coil will pass through one of the two remaining coils and will envelop the other remaining coil as indicated in Figure 4. Also, I preferably bow the cross-over legs 18b outwardly from the pivot axis so as to provide a central opening 19 through which the rotor magnet may be passed without disturbing the coils.

In Figures 8 and 9 there is illustrated another receiver according to my invention wherein there is again obtained the torque deflection characteristic between the magnet and field coils represented by Figure 2; hence, the value for b in this design is again $-.052$. This receiver comprises a magnet 20 pivoted at 21, a surrounding concentric shield such as the shield 17 and three identical field coils 22 which are interposed between the magnet and shield. The field coils are arcuately shaped so that they will lie wholly within the space between the magnet and the shield, but it will be understood that each coil may be made flat and will have the same operating characteristics so long as the span of the coils and the width of their longitudinal legs remain the same. The rotor magnet 15 used with this embodiment is a flat disk of "Alnico" about $\frac{3}{16}$ " thick having diametrically opposite end portions with flat bevels 24. As typical values, for a shield of 1" diameter, the magnet may be $\frac{5}{8}$ " in diameter, the thickness at the tip, $\frac{3}{16}$ ", and the separation of the parallel lines 23 from where the bevels begin, $\frac{1}{4}$ ". This magnet is magnetized on a central line running through its beveled ends and has a flux field distribution approximately as shown in Figure 10. By Fourier analysis, the fraction of third harmonic in this flux distribution curve is $+.054$.

On selecting a span for each coil of 90° ($x=45^\circ$) and using the values of $-.052$ and $+.054$ for b and d respectively, Equation 4 specifies that g shall be 10° —that is, that the width of the longitudinal legs 22a of each coil shall be 20° . For these values, there will again be obtained a substantially linear response.

In Figures 11, 12 and 13 I show another embodiment of receiver according to my invention wherein there are employed two field coils per phase, or a total of six coils. This receiver comprises the cylindrical shield 17, a centrally pivoted magnet 25 and three similar sets of coils 26, 27 and 28, of which each set comprises two coils connected preferably in series, the coils for set 26 being 26a and 26b, etc. In the circuit of Figure 1, these coil sets replace the single field coils per phase as used in the foregoing embodiments. The coil 26a passes through the coil 26b of its own set, and is accordingly made shorter in its dimension running axially of the meter, but all

coils are alike in respect of their span about the pivot axis as a center and the width of their longitudinal legs 26c. Each coil set may be considered as having an effective magnetic axis 5 which is analogous to the coil axis of each single coil considered in the foregoing embodiments. By way of illustration the effective axis for coil set 26 is designated as A in Figure 11. The angular spacing of these effective axes is again at 120° intervals about the pivot axis. The coils of each set may be positioned at angles to the effective axis A, but will be symmetrically disposed thereto as shown. The angular span between the two longitudinal legs nearer the effective axis A may be termed $2x$, and that between the other two legs which are farther from the axis A, $2w$, x and w being then the angular spacing of the longitudinal legs from the effective magnetic axis of the coil set. Using g , b and d with the same significance as before, I find by my invention that receivers using two coils per phase will have a substantially linear response when

$$25 \quad 4(\sin^2 x - \sin x \sin w + \sin^2 w) = 3 - \frac{3b}{d(3 - 4 \sin^2 g)} \quad (5)$$

or, alternatively, by expressing b in terms of r/l and transposing terms, when

$$30 \quad d = \frac{39r/l}{(3 + r/l)(3 - 4 \sin^2 g)[3 - 4(\sin^2 x - \sin x \sin w + \sin^2 w)]} \quad (5a)$$

The magnet 25 which is preferably used with this embodiment is shown in Figures 12 and 13. This magnet consists of a disk of "Alnico" having diametrically opposite segment portions cut off to form a pair of peripheral flats 25a. By way of example, the magnet may have a diameter of $\frac{5}{8}$ ", a length from flat to flat of $\frac{1}{2}$ " and a uniform thickness of $\frac{1}{16}$ ". The magnet is charged on a diameter line running centrally through the flats 25a.

The magnet above described has approximately the flux curve shown in Figure 14. This curve measures to have a fraction of third harmonic of $+.125$. As typical and convenient values of the field coils, each coil of each set may have a span of 100° about the pivot axis and the two coils of each set may be spaced 60° apart—that is, at plus and minus 30° from the magnetic axis A of the set. Each coil set thus has a pair of legs nearer to the effective axis A which have a span of 60° from each other and another pair farther from the axis A which have a span of 140° from each other. The value of x and w for each coil set is thus 30° and 70° respectively. The angular width of each coil leg may be 16° , giving g a value of 8° . Using these values in Equation 5, with a value for d of $+.125$ as above mentioned, b computes to be $-.043$. Using this value of b in Equation 2, the ratio r/l is computed to be approximately 1.5. This means the resistance of each transmitter section shall have approximately 1.5 times the resistance of each field coil, for the values above chosen, in order to obtain a linear response.

In Figure 15, I show another embodiment of receiver utilizing two field coils per phase, which is the equivalent in operation to the receiver of Figure 11. This receiver comprises the cylindrical shield 17 and magnet 25 as in the embodiment of Figure 11, and has three sets 30 of field coils of which each set consists of two coils 30a and 30b. In this case, however, the coils of each set are parallel and axially aligned with each other, the smaller coil 30a having a mean span

of approximately 60° and the larger coil a span of approximately 140° . In the arrangement of the three sets of coils in the assembled meter, a leg of the larger coil of each set lies between the legs of the larger and smaller coils of the next succeeding set. The horizontal or cross legs of the larger coils thus overlap one another as indicated in Figure 15; to permit this overlapping the larger coils are made of different length, axially along the meter, their angular spans about the pivot axis being however the same.

The corresponding values of x and w with this coil arrangement are accordingly 30° and 70° , the same as with the arrangement of Figure 11. Upon making the angular width of the coil legs also 16° , g will have a value of 8° and d will again be by Equation 5 equal to $+12.5\%$, giving therefore the same flux distribution characteristic as is shown in Figure 14.

The three specific embodiments hereinabove shown and described are examples of the various arrangements possible by my invention, and are presented to illustrate the relationships between the significant parameters of the telemetric system which are basic to obtaining a substantially linear response. It will be understood that innumerable other embodiments are possible within the range of these relationships. It will be further understood that these embodiments of my invention are in other respects illustrative and not limitative thereof and that within the range of engineering skill and by use of the equations herein presented various changes and modifications may be made therein without departure from the scope of my invention which I endeavor to express according to the following claims.

I claim:

1. In a telemetric system including three like transmitter resistances serially connected in closed circuit arrangement, and a single contact for traversing said resistances and a D.-C. source of potential: a receiver comprising a pivoted permanent magnet and a plurality of field coils spaced at intervals around the pivot axis of said magnet and connected as an electrical Y, the outer terminals of said Y being connected to the respective junctions between said transmitter resistances, means connecting said source of potential between said contact and the center of said Y for causing said field coils to be energized to produce a torque-directing influence on said magnet according to the positioning of said contact, said magnet and said coils being shaped to produce a restoring torque on said magnet which varies, upon said contact being held at a given fixed position and the magnet being deflected from an equilibrium position, according to a Fourier series comprising a fundamental and a fraction of third harmonic equal substantially to

$$-\frac{13r/l}{3+r/l}$$

where r/l is the ratio of the value of each of said transmitter resistances to the resistance between the center and outer terminals respectively of said Y.

2. In a three-phase telemetric system including a closed transmitter element of substantially uniform resistance having three taps at substantially equal resistance intervals, a single contact for traversing said resistance element and a D.-C. source of potential: a receiver comprising a pivoted permanent magnet, an arrangement of

field coils connected as an electrical Y and having three effective magnetic axes spaced substantially equidistantly about the axis of rotation of said magnet, and a magnetic shield surrounding said field coil arrangement and substantially concentric to the pivot axis of said magnet, the space between said magnet and shield being free of magnetic materials, the outer terminals of said Y being connected to the junctions between said transmitter resistances; and means connecting said potential source between the center of said Y and said contact, said magnet and said coils being shaped to produce a restoring torque on said magnet which varies, upon said contact being held to a given position and the magnet being deflected from an equilibrium position, according to a Fourier series comprising a fundamental and a fraction of third harmonic equal substantially to

$$-\frac{13r/l}{3+r/l}$$

where r/l is the ratio of resistance between the taps of said transmitter element to the resistance between the center and outer terminals respectively of said Y.

3. The telemetric system set forth in claim 2 wherein said field coil arrangement consists of three similar coils, and said magnet is shaped to have a flux field whose strength varies around the magnet according to a Fourier series comprising a fundamental and a fraction of third harmonic equal substantially to

$$\frac{.39r/l}{(3+r/l)(3-4\sin^2 g)(3-4\sin^2 x)}$$

where r/l is the ratio of the value of each transmitter resistance to the resistance of each field coil, x is one-half the angular span in degrees of each field coil about said axis and g is one-half the angular width in degrees of each leg of said coils about said axis.

4. The telemetric system set forth in claim 2 wherein said field coil arrangement consists of three similar coils, and said magnet is shaped to have a flux field whose strength H in the space between the magnet and said shield varies, at angles ϕ about said pivot axis from the magnetic axis of the magnet, substantially according to the equation

$$\sin \phi + d \sin 3\phi$$

where d is the fraction of third harmonic, and the dimensions of the legs of each field coil in said space between the magnet and shield are according to the relation

$$(3-4\sin^2 g)(3-4\sin^2 x) = \frac{.39r/l}{(3+r/l)d}$$

where g is one-half the angular width in degrees of each coil leg about said pivot axis, x is one-half the angular span in degrees of the legs of each coil about said pivot axis, and r/l is the ratio of the value of each of said transmitter resistances to the resistance of said respective field coils.

5. In a telemetric system including a transmitter of the single-contact type: a receiver for said system comprising a pivoted permanent magnet, three similar field coils connected as an electrical Y and spaced angularly about the pivot axis of said magnet, and a cylindrical magnetic shield surrounding said coils and magnet, each of said coils having substantially a 180° span about said pivot axis as a center, said magnet being symmetrical to its pivot axis and having a

substantially ellipsoidal shape as viewed along its pivot axis, and said magnet being charged along its major elliptical axis.

8. The telemetric system set forth in claim 2 wherein said field coil arrangement comprises three similar field coils each having a substantially 90° span about said pivot axis as a center, and wherein said magnet has a disk shape with beveled pole end portions.

7. The telemetric system set forth in claim 2 wherein said field coil arrangement consists of three like pairs of field coils, and said magnet is shaped to have a flux field whose strength varies around the magnet according to a Fourier series comprising a fundamental and a fraction of third harmonic equal substantially to

.387/l

$$(3+r/l)(3-4\sin^2 g)[3-4(\sin^2 x-\sin x\sin w+\sin^2 w)]$$

where r/l is the ratio of the value of each transmitter resistance to the resistance of each coil pair, g is one-half the angular width in degrees of each leg of each field coil which is in the space between the magnet and said shield, and x and w are the angular spacings in degrees between the effective axis of each coil pair and the coil legs of that pair to each side of that axis.

8. The telemetric system set forth in claim 2 wherein said coil arrangement comprises three pairs of field coils, each of said pairs having two legs at each side of the effective magnetic axis of the pair of which one leg is spaced by approximately twice the angular distance from said axis than is the other leg, and wherein said magnet has the shape of a disk provided with two diametrically opposite peripheral flats and is charged on a diameter line running centrally through said flats.

9. The combination set forth in claim 1 wherein in said receiver has three field coils spaced angularly at approximately 120° intervals and each coil has approximately a 180° span.

10. A telemetric receiver for a telemetric system of the three-wire, single-brush transmitter type, comprising a permanent magnet pivoted on an axis through the center thereof with the magnetic axis of the magnet at substantially right angles to said pivot axis, three field coils positioned at 120° intervals about said pivot axis with the magnetic axes of the coils radial to said pivot axis, said coils surrounding said magnet and spanning 180° respectively with respect to

said pivot axis, and a magnetic shield surrounding said coils and symmetrically disposed with respect to said pivot axis.

11. In a telemetric system of the three-wire type comprising a closed transmitter resistance having a single brush: the combination of a receiver comprising a pivoted permanent magnet having the magnetic axis thereof substantially at right angles to its pivot axis, three field coils surrounding said magnet respectively and spaced at 120° intervals about said pivot axis, said coils having respectively 180° spans about said pivot axis and being interconnected to have a neutral terminal, and a magnetic shield surrounding said coils and symmetrically disposed with respect to said pivot axis; and means for connecting a source of potential between said brush and said neutral terminal.

12. In a telemetric system of the three-wire, single-brush transmitter type: a receiver comprising a pivoted permanent magnet having its magnetic axis crosswise to its pivot axis, three substantially identical field coils extending one through the other and spaced at 120° intervals about said pivot axis, said coils respectively having longitudinal legs spaced substantially 180° about said pivot axis with one longer than the other, and said coils having cross-over legs that overlap one another.

13. In a telemetric system of the three-wire, single-brush transmitter type: a receiver for said system comprising a permanent magnet of an approximately ellipsoidal shape having its magnetic axis corresponding with its major geometrical axis and pivoted at the center of the magnet on an axis at right angles to its magnetic axis, and three field coils positioned at 120° intervals about said pivot axis with the magnetic axis thereof radial to said pivot axis, said coils spanning respectively approximately 180° about said pivot axis.
